UNITED STATES PATENT OFFICE.

GEORGE J. PALMER, OF WEST CHESTER, PENNSYLVANIA.

HUMIDIFIER FOR RADIATORS.

No. 902,905.

Specification of Letters Patent.

Patented Nov. 3, 1908.

Application filed February 28, 1908. Serial No. 417,948.

To all whom it may concern:

Be it known that I, GEORGE J. PALMER, a citizen of the United States, residing in West Chester, Pennsylvania, have invented certain 5 Improvements in Humidifiers for Radiators, of which the following is a specification.

One object of my invention is to provide a humidifier which can be attached or coupled to a radiator in such a manner that it 10 will seem part of the radiator structure.

A further object of the invention is to so place the humidifier that both walls of the humidifier will be heated by being in close proximity to the radiating surface.

15 These objects I attain as hereinafter set forth, reference being had to the accompanying drawing, in which:

Figure 1, is a side view, partly in section, illustrating my humidifier as applied to the 20 center of a radiator group; Fig. 2, is a plan view of Fig. 1; Fig. 3, is a detached perspective view of the humidifier; Fig. 4, is a perspective view of the cover; Fig. 5, is a sectional view illustrating a modification; Figs. 25 6 and 7, are side views illustrating the humidifier at one end of the group of sections instead of in the center as illustrated in Fig. 1; Figs. 8 and 9, are sectional views illustrating other modifications of my invention, 30 and Fig. 10, is a side elevation of the structure shown in Fig. 5.

It will be understood at the outset that my invention can be applied to any form of 35 radiator made of sections and the design of the radiator may be varied, but where possible the design of the humidifier follows the design of the radiator so that when the parts are assembled the humidifier part resembles the radiator sections.

40 Referring in the first instance to Figs. 1 and 2, the radiator is made up of a series of sections A—A in the present instance coupled together at a—a forming a communication between the supply pipe c and the several radiator sections. c' is a valve for regulating the flow of steam or hot water to the radiator, and a' is a nipple or pipe coupling the two radiator sections together on each side of the humidifier B. This humidifier, 45 in the present instance is made of cast iron and similar in shape to the radiator sections A and has a passage b in its lower end which extends from one side to the other of the humidifier, but does not communicate with 50 the interior thereof; the nipple a' extends

through this passage. At the upper end of the humidifier are passages b' which extend from one side to the other. These passages likewise do not communicate with the interior. These passages are formed in the humidifier section the same as in the radiator sections and are made to receive the confining rods e—e which fasten the sections together in the present instance, but other means of fastening may be resorted to without departing from the essential features of my invention.

The arrangement of the through passages may vary according to design or type of radiator to which the humidifier is applied. In Fig. 8 I have shown a humidifier section B⁴ having a passage b³ at its lower end and a similar passage b⁴ at its upper end; this form is used especially in connection with hot water radiators.

75 In the present instance the humidifier section B has a removable cap D with a number of perforations d therein and this cap is flanged at d'; the flange extending within the radiator section B when the cap is in position. By this construction the cap can be removed and the humidifier can be filled with water or other liquid.

In the bottom of the humidifier section B is a drain opening b², which can be provided 80 with a suitable valve for drawing off the water when it is desired to empty the humidifier. The side walls f—f of the humidifier are made preferably very thin and each wall being in close proximity to a radiator section the vaporization of the water will be more rapid than where the humidifier is placed at the back of the radiator or on top of it as is the common practice at the present time and a much larger area of the humidifier is subjected to heat.

90 The humidifier section may be made as shown in Figs. 5 and 10, in which case the frame B' is of cast metal and has inserted in it a tank B² made of sheet metal; the sides of the frame being open so that the thin walls of the tank will be in close proximity to the radiator sections. Some types of radiators are made entirely of sheet metal and in this event the humidifier section 95 would preferably be made of sheet metal, or a sheet metal humidifier may be used in connection with a cast metal radiator if found desirable.

100 In Fig. 7, I have shown the humidifier 105

section B at one end of the radiator; this section being similar to the section B illustrated in Fig. 1.

In Fig. 6, I have shown a slight modification of the humidifier section; the section B³ being secured to the radiator by rods *c* and this section B³ stops short of the steam supply, hot water supply or exhaust pipe.

In radiators in which a single pipe communicates with one end of the radiator, I may extend the humidifier section the full depth of the radiator section, as in Figs. 1 and 7, and attach it to the end of the radiator opposite, to the end of which the supply pipe is connected.

In Fig. 9, I have shown the humidifier section B⁵ with holes in the walls and the screw threaded nipple *a*² passes through the holes and is adapted to threads in the radiator sections A, gaskets being used between the sections to prevent leakage.

It will be seen from the above description that I can readily attach my improved humidifier to radiators already in position without dismantling them, or I can place the humidifier in position at any point in a group of radiator sections prior to their being assembled or set up in position. The latter method is preferred as I am enabled to locate the humidifier that its surface will be in close proximity to the heating surface of the radiator. It will also be understood that the shape of the holes in the cap may be modified according to the design of the radiator and in some instances the cap may form an integral part of the humidifier as in Fig. 8, the holes can be of sufficient size to allow the water to be poured into the humidifier through the holes.

40 I claim:

1. The combination of a radiator made up of a series of sections, a humidifier made to resemble one of said sections and secured to the radiator in close proximity to one of the 45 radiator sections so that the side walls of the humidifier will be heated to vaporize the water contained in the humidifier.

2. The combination of a radiator made up of a series of vertically arranged sections, 50 with a vertically arranged humidifier section shaped to resemble one of the radiator sections and assembled between two of the sections of the radiator, said humidifier section extending from one side of the radiator to the other.

3. The combination of a radiator made up of a series of sections, a humidifier made to resemble one of said sections and situated in close proximity to one of the radiator sec-

tions so that the side walls of the humidifier 60 will be heated to vaporize the water contained in the humidifier, and longitudinal rods tying the sections together, said rods passing through passages formed in the humidifier section and securing said humidifier to the radiator sections.

4. The combination of a radiator made up of sections connected together and to a supply pipe, a humidifier section adapted to contain fluid, said humidifier section having a 70 through passage out of communication with its interior, and a nipple extending entirely through the said passage and coupled to a radiator section on each side of the humidifier so that the circulation through the radiator 75 is not interfered with by the humidifier.

5. The combination of a radiator made up of a series of connected sections, a supply pipe attached to one end of the radiator, said radiator sections being spaced apart, a 80 humidifier made to resemble a radiator section and having a through passage extending from one side to the other, but not in communication with the interior of the humidifier, a nipple extending through the passage, and 85 coupling the two radiator sections on each side of the humidifier, and a removable cap for the humidifier, said cap having perforations therein.

6. The combination in a radiator made up 90 of a series of sections coupled together, one section communicating with another, a humidifier shaped to conform to the general shape of one of the radiator sections and secured at the side to one of said sections so 95 that the side of the humidifier will be in close contact with the side of the radiator section, a detachable, perforated cap for the said radiator section, said humidifier having an outlet at the base to draw off the water.

7. The combination of a radiator with a humidifier shaped to resemble the shape of the radiator and attached thereto so that the side of the humidifier will be in close proximity to the side of a radiator section, the 105 humidifier being made in two parts, of which one consists of a frame open at one side and the other part consists of a tank mounted in the frame and having its side exposed through the side opening thereof so that the 110 water in the tank will be heated.

In testimony whereof, I have signed my name to this specification in the presence of two subscribing witnesses.

GEO. J. PALMER.
